W. BELL

MATERIAL HOLDER AND CARRIER FOR DYEING YARN ON CHEESES

Filed July 26, 1923

FIG. 1

FIG. 3

Patented July 1, 1924.

1,500,046

UNITED STATES PATENT OFFICE.

WALTER BELL, OF HAMILTON, ONTARIO, CANADA.

MATERIAL HOLDER AND CARRIER FOR DYEING YARN ON CHEESES.

Application filed July 26, 1923. Serial No. 653,996.

To all whom it may concern:

Be it known that I, WALTER BELL, a subject of the King of Great Britain, and a resident of the city of Hamilton, in the county of Wentworth, Province of Ontario, Dominion of Canada, have invented certain new and useful Improvements in Material Holders and Carriers for Dyeing Yarn on Cheeses, of which the following is the specification.

My invention relates to material holders and carriers for dyeing yarns on cheeses and the object of the invention is to devise an improved type of holder and carrier for this purpose which will be more convenient and economical to use than those formerly used; a further object is to facilitate the complete unwinding of the cheese so that there will be no tendency for the carrier to interfere with the free unravelling of the yarn off the cheese during the unwinding operation. Other objects will appear hereinafter.

My invention consists essentially of a holder and carrier comprising a coil spring, the ends of which are encased in perforated encasing elements, and a strip of covering material being wrapped about the spring and encasing elements, all as hereinafter more particularly described and illustrated in the accompanying drawings in which:

Fig. 1 is a view of my improved holder and carrier, the lowermost of two end encasing elements used therewith being shown in section.

Fig. 2 shows a quantity of yarn wound upon my improved carrier and forming what is known in the art as a cheese, the yarn and a strip of material covering the carrier being shown in section.

Fig. 3 is a diagrammatic side elevation of a form of kettle used for dyeing yarns, a portion of the wall being broken away to show the interior. For the sake of clearness, only a portion of the interior contents have been illustrated.

Fig. 4 is a sectional view of a clamping ring used in connection with the kettle illustrated in Fig. 3.

In the drawings like characters of reference indicate corresponding parts in the different views.

1 indicates collectively my improved holder and carrier.

This comprises the coil spring 2 the ends of which carry the encasement elements 3.

These elements 3 constitute sleeves which

encase the end portions of the spring 2 and are each provided with the inwardly bent flange 4 which engages the end of the spring and limits the penetration of the spring into the sleeve. The sleeves may be secured to the spring by the pins 5.

The sleeves 3 are provided with a series of perforations 6 which are helically disposed about the sleeves and register with the interstices between adjacent coils of the spring.

7 is a strip of jute or other suitable textile material which is wrapped about the spring 2 and sleeves 3 and forms a covering therefor.

The spring 2, sleeves 3 and covering 7 constitute a holder and carrier upon which yarn may be wound.

The parts illustrated in Fig. 2 showing the yarn 8 wound upon the holder constitute what is known in the art as a cheese, 9 being the free end of the yarn.

For convenience these cheeses will be hereinafter referred to by the numeral 10.

11 is a cylindrical kettle having the false bottom 12 which divides the kettle into the upper chamber 13 and the lower chamber 14.

15 is a cover plate secured to the flanged top 16 of the kettle by bolts 17.

This cover seals the upper end of the kettle.

18 are pipes the lower ends of which are secured to the false bottom 12 and communicate with the lower chamber 14.

These pipes are provided throughout their length with perforations 19.

20 is a pipe communicating upwardly through the false bottom 12 and 21 is a valve in said pipe.

22 is a pipe communicating with the bottom of the chamber 14 and 23 is a valve therein.

24 are clamping rings detachably mounted upon the upper ends of the pipes 18 and are provided interiorly with L-shaped slots 100 25 adapted to engage pins 26 near the upper ends of the pipes 18. The purpose of these will appear hereinafter.

The operation of my invention is as follows.

Before winding the yarn to be dyed upon the holder, the covering material 7 is wrapped thereabout. Any old scrap material such as jute sacking may be used for this purpose.

The yarn 8 is then wound, in the usual manner, upon the holder, the material 7 con-

stituting a foundation for the innermost windings of the yarn.

When this operation is completed the parts are as illustrated in Fig. 2 and constitute a cheese.

These cheeses are then inserted within the kettle, being piled one upon the other so that the pipes 18 pass upwardly therethrough.

- 10 The clamping rings 24 are then mounted upon the upper ends of the pipes 18, these rings being pressed downwardly so that the springs 2 and the cheeses as a whole are compressed and forced tightly together.
- 15 As the clamping ring is pressed downwardly the pin 26 passes upwardly in the slot 25 and by giving the ring a slight turn the pin 26 passes into the off-set end portion of the L-shaped slot 25 and secures 20 the ring against longitudinal motion.

In this position the cheeses are tightly compressed together.

While only a few of the pipes 18 and of the cheeses 10 have been included in Fig. 3 25 it is to be understood of course that the kettle will contain as many of these as possible.

The construction and operation of the kettle itself is of standard type and forms 30 no part of my present invention and therefore detailed description is not thought necessary.

The operation of dyeing yarn in such a kettle however may be briefly stated as follows.

When the cheeses have been properly mounted in position upon the pipes 18 the cover 15 is secured in place. The dyeing solution is then pumped in, say through the 40 pipe 22, and enters the bottom chamber 14 from which it passes upwardly into the pipes 18 and out through the perforations 19 in these pipes.

It is then forced outwardly through the 45 cheeses and enters the upper chamber 13 from which it passes downwardly through the false bottom 12 into the pipe 20. The

direction of flow in this operation is indicated by the arrows in Fig. 3.

When this flow has continued for a sufficient length of time it may be reversed in direction and made to flow inwardly through the pipe 20 and outwardly through the pipe 22. In this case instead of flowing outwardly through the cheeses it flows inwardly therethrough from the chamber 13 into the pipes 18.

I am aware that coil springs have been used for this purpose but their use has not proved satisfactory for various reasons, one of which has been the difficulty of unwinding the cheese, it having been found that the end of the spring interferes with the free unravelling of the yarn.

Formerly these springs have been covered by a knitted stockinette. This had the disadvantage that it was expensive and difficult to put on and take off the spring, the operation requiring considerable time and usually the stockinette was damaged in the 70 operation.

Further the ends of the stockinette interfered with the free unravelling of the yarn.

It is to be noted that the perforations 6 in the sleeves register with the interstices between adjacent coils of the spring and thus permit free passage of the dyeing liquid therethrough.

From the foregoing it will be observed that I have devised valuable improvements in 60 holders and carriers for the purpose specified which will prove of great value.

What I claim as my invention is:

A material holder and carrier of the class described comprising a coil spring, and a sleeve encasing each end thereof, each sleeve provided with a series of helically disposed perforations registering with the interstices between adjacent coils of the spring.

WALTER BELL.
